UNITED STATES PATENT OFFICE.

SAMUEL H. BARTLETT AND HENRY E. WAITE, OF BRIDGEPORT, CONNECTICUT, ASSIGNORS TO CHARLES F. LIVERMORE, OF NEW YORK, N. Y.

TELEPHONE-RELAY.

SPECIFICATION forming part of Letters Patent No. 251,400, dated December 27, 1881.

Application filed August 31, 1881. (No model.)

To all whom it may concern:

Be it known that we, SAMUEL H. BARTLETT and HENRY E. WAITE, both of Bridgeport, county of Fairfield, State of Connecticut, have 5 invented new and useful Improvements in Telephone-Relays, of which the following is a full, clear, and exact description, reference being had to the accompanying drawings, making part of this specification, in which—
10 Figure 1 is a plan or top view of our improved telephone-relay. Fig. 2 is a vertical section through the same, and Figs. 3 and 4 are vertical sections at right angles to Fig. 2 through the supports for the armature to the magnet.
15 Our invention relates to a novel relay for telephones for imparting or communicating a message delivered to and conveyed by one line to another, and independent line or lines by which it is further conveyed to the desired 20 point; and it consists in the combination, with the magnet and its coil or helix closing the circuit at the end of one line, of an adjustable armature or plate of steel or other magnetic metal, through which connection is made with and 25 which forms a part of the transmitter of another and independent telephone line or circuit, whereby the message imparted to and conveyed by one line is communicated to and transmitted by another and independent line, as 30 hereinafter explained.

It further consists in a novel arrangement of microphones and of split circuit or connections therewith in the transmitter portion of the relay, whereby the action of the latter is greatly 35 improved, as hereinafter explained.

In the accompanying drawings, A represents a base-plate, of wood, rubber, or other suitable non-conducting material, upon which are arranged suitable uprights or supports, C C' C², 40 for the support of the parts of the relay. The support or upright C is adapted to receive and support a magnet, D, having upon one end a coil, D', in which the wires d d' of a first telephone line or circuit terminate. This line is 45 complete in itself, being provided at the end opposite to the magnet C with a transmitter, T, of any preferred form or construction, and at any suitable point, connecting with a battery, B, through which the disturbances in the 50 current in the transmitter are conveyed to the magnet D at the receiver end of the line.

Just in front of the end of the magnet D which projects through the coil is arranged a thin flat plate or strip, F, of steel or other magnetic material, which serves as a flexible armature to the magnet, and to which the disturbances in the latter are communicated. This plate is supported rigidly at one end in an upright, C², which has a vertical slit in its upper end to receive the end of the strip or plate F, 55 and is provided with a clamping thumb-screw, G, for clamping the strip F firmly between the arms of the standard, as shown in Fig. 2.

The standard C² is made adjustable upon the bed-plate A, in a path at right angles to the 60 axis of the magnet, by means of slots formed in the bed-plate at a a', and suitable set-screws, h h', and nut-plate H, for clamping and holding the standard at any desired point. The plate F also has a longitudinal slot formed in 65 it at f, where the clamping-screw G passes through it, this arrangement permitting the support for the plate to be set nearer to or farther from the axis of the magnet, for stiffening or for giving increased flexibility to the plate 70 F, as may be required, by moving its point of support nearer to or farther from the magnet, its disturbing agent. The opposite or free end of the strip or plate F rests midway, or thereabout, between two vertical arms, C³ C⁴, of upright or bracket C', (see Figs. 1 and 3,) and is 75 provided on its opposite vertical sides or faces with spurs or points i i', which may be of platinum, carbon, or other suitable conducting material.

The arms or lugs C³ C⁴ have each a screw, k k', provided on its inner end with a piece or button, l l', of carbon, against which the points i i' rest or vibrate as the plate F is vibrated or disturbed by the action of the magnet or of the 80 disturbances therein. The screws k k', or the carbons connected therewith, have each a short wire, m or m', connected with it, terminating by split connection in a line-wire, d³, of a second telephone line or circuit. The other wire, 85 d⁴, of this second line is connected with the end of plate F, secured in the upright C², either through the clamping-screw G, as shown, or in any other suitable manner.

The wires d³ and d⁴, which through the connections described, are made to receive the disturbances in the magnet D, form an independ- 900

ent telephone line or circuit provided with its own battery, B', and terminating in any preferred form of receiver, R, or in a second relay similar to that above described, through 5 which disturbances in said line are imparted to still another independent line.

The arrangement of the plate or armature F, in connection with the adjustable buttons l' of carbon or equivalent conducting material, upon its opposite sides, is such that the movement of or disturbance in the current in the plate or strip is carried out from both sides thereof to the line-wire of the second or relay line through the split connection described— 15 an arrangement which has been found to greatly increase the effectiveness of the apparatus, while the arrangement for adjusting the tension of the arm or plate F, or its power of resistance to the action of the magnet, as described, enables us to adapt it with precision to the requirements of the battery-power employed, and thereby to secure the best possible results.

It will be apparent that variations in the current in the coil producing disturbances in degree of polarity in the magnet will cause corresponding disturbances in the flexible armature, and when the latter is drawn inward toward the magnet, deflecting it slightly from a 25 right line, it will cause the point i to press with increased force upon the button l, while at the same time such deflection will tend to produce a scratching action of the points i and i' upon the carbons, more particularly of the point i' 30 on the carbon l', the spur i acting somewhat as a pivot for the spur i' to vibrate upon. Supposing the equilibrium to be restored, and the armature to be then repelled or deflected outward away from the magnet, a reverse action 35 of the points or spurs i and i' to that above described takes place. In this way, through the buttons l and l', connecting with the same pole of the armature and having a split connection with the line, we are enabled to more 40 fully utilize the disturbances in the flexible armature than we could by using the carbon on one side only thereof, and we therefore prefer the arrangement described.

We would state that we are aware that relays have been used in telephone-lines; but 50 these, so far as we are aware, have only been adapted to short lines or branches not employing an independent battery for the transmission of the message imparted to it, and which consequently received and carried forward the 55 induction of the main or battery line or circuit. In our arrangement the relay is designed for use at the terminus of one line after the message has been carried as far as is found to be effectively practicable under all the varying 60 conditions of atmospheric changes, &c., and then, by interposing the relay, to communicate the disturbances in the current of the first line to a second and independent line, over which the message is conveyed by the power of its 65 own battery, without communicating to or carrying forward thereon the induction of the first line.

By our construction and arrangement we are 70 enabled to convey telephonic messages to any desired distance without increasing the inductive action at the receiving-point beyond what is due to the length of the independent terminal line and the amount of battery-power employed thereon.

Having now described our invention, we 75 claim—

In a telephone-relay, the combination, with an electro-magnet forming the terminus of a telephone line or circuit, of an adjustable spring- 80 armature rigidly supported at one end, with its free end resting between adjustable carbon buttons, having a split connection with an independent telephone-line having its terminus 85 in said buttons and armature, said parts being arranged and operated substantially as and for the purpose described.

In testimony whereof we have hereunto set our hands this 30th day of August, A. D. 1881.

SAMUEL H. BARTLETT.
HENRY E. WAITE.
